UNITED STATES PATENT OFFICE

BENJAMIN K. TAKENAKA, OF NEW ROCHELLE, NEW YORK

POST FOR INTERCHANGEABLE TEETH

Application filed April 10, 1929. Serial No. 353,959.

This invention relates to interchangeable artificial tooth facings and casting posts whereby said facings may be firmly and readily secured to cast metal bases or backings, which in turn are adapted to be secured to a denture, portion of bridgework or other dental structure.

An object of this invention is to provide a strong rigid artificial backing of cast gold or other metal or of moldable material which can be hardened, which is designed for heavy duty and which cannot crack or deform under the stress imposed by biting or chewing.

15 Another object is to provide an artificial tooth of pleasing and natural appearance without sacrificing the features of strength and rigidity hereinabove mentioned.

Another object is to provide a novel interlocking or securing means whereby the casting post is positively engaged and locked in the metal casting or other base, making it impossible for it to work loose, and affording a snug and firm fit for the interchangeable 25 tooth facing.

Other features of this invention will be readily understood by those familiar with the art; these include a simplicity of construction and ease of replacing damaged facings, and 30 economy of manufacture.

The invention is adapted for artificial anterior or posterior teeth and relates to the art of interchangeable tooth bridge construction, but its adaptability for other dental 35 structures is apparent from the accompanying description.

The manner of carrying out the above mentioned objects will appear from the novel design, construction and combination of parts 40 hereinafter described and claimed and shown in the accompanying drawings, in which,

Figure 1 is an elevational view, partly in section, taken in a vertical plane through the approximate center of a cast molar tooth 45 made in accordance with this invention, showing one form of casting post unit in position.

Figure 2 is a vertical sectional view of an incisor tooth, similarly constructed.

Figure 3 is a transverse sectional view on 50 line 3—3 of Figure 1.

Figure 4 is a perspective view of the casting post unit shown in Figures 1, 2 and 3.

Figure 5 is a perspective view of a modification of the casting post unit shown in Figures 1, 2, 3 and 4.

Figure 6 is a transverse sectional view similar to Figure 3 with the modified form of casting post unit in place in the finished casting. This view is taken to illustrate two different half sections as indicated by line 55 60 6—6 of Figure 7.

Figure 7 is an elevational view of the inside of a facing before it is fixed in the casting, with the modified casting post unit fitted in place in a groove provided therefor in the 65 facing.

Figure 8 is a perspective view of the inner side of a grooved facing used with this invention.

Figure 9 is a sectional view of a portion 70 of the human jaw, showing the invention in dotted outline in position inside of cast incisor teeth.

Figure 10 is a perspective view of a number of teeth in the lower jaw, showing two 75 cast molars attached as an inlay.

In the drawings 1 indicates the casting post, 2 a rib connecting the post to the plate, 3. The post, rib and plate are herein referred to collectively as a casting post unit or as 80 a post unit. The plate 3, as shown in Figure 4, is provided with beveled edges 4. The provision of these beveled edges produces a positive interlock into the metal tooth casting as is apparent in Figures 1, 2 and 3 wherein 85 the metal casting 5 is shown to have filled in in front of the tapered facing 4 of the casting post unit so to rigidly fix it to the casting. This construction not only ensures positive anchoring of the casting post unit into 90 the casting, but also provides a smooth, well-formed planar face 6 against which the facing 7 can seat, without the necessity of filing or grinding to fit. The facing 7 is made of porcelain or similar material and 95 is illustrated in perspective in Figure 8. It contains a longitudinal groove 9 with an undercut tubular space 10 thereunder adapted to fit over post 1. These facings are manufactured to fit tightly against the faces 6 100

of the post units, which are embedded in the castings as follows:

A desired facing is positioned over the post of the casting post unit and said unit is embedded in wax in order that the wax hold the unit in place by filling in in front of the beveled edges 4. The wax is molded into the form of the tooth desired to be constructed, the facing removed and the wax model and casting post unit embedded in a creamy mixture of casting investment which fills in about the post 1 and around the wax model, making an exact form therefor. The investment is allowed to set and when hard and dry is thrust into a fire. During this operation the wax is burned out, the products of combustion escaping through a small hole provided in the investment mold by withdrawing a very small rod previously inserted in the wax model. The casting post unit is thus held in proper position by reason of the investment mold holding the pintle in the position in which it had been held by the wax model. A suitable metal is cast into the mold through the hole through which the burning wax escaped, and fills in the interstices formerly occupied by the wax model, and as illustrated in Figures 1, 2 and 3. Thus the unit practically dovetails into the backing.

When locked in the castings as above described the posts 1 are securely held in the front face of the casting, and seating surfaces 6 are provided against which the facings may be accurately and firmly positioned. It is to be noted that the front of the casting post plate is in exact alignment with the front edge of the casting and thus forms a partial backing for the facing. The facing, having been fitted in its place against the wax mold, must of necessity possess the identical accurate fit against the finished casting. Thus an exact fit is obtained without having to file or grind down any part of the backing.

In the modification illustrated in Figures 5, 6 and 7 the casting post unit is provided, instead of beveled edges, with beaded or punched-out portions 8 which have the appearance of semi-circular tabs as viewed from the back as in Figure 7. In a manner similar to that in which the metal casting covers the front edges of the bevels 4 in the unit shown in Figure 4, so does the casting fill in the spaces above and in front of the tabs 8 and lock this unit in place. This locking is clearly shown in Figure 6.

It has heretofore been attempted to provide fins on casting posts, designed to extend into metal castings for the purpose of anchoring same. These fins have proved highly inefficient and unsatisfactory inasmuch as a positive locking-in could not be obtained, and also for the reason that said fins have been found to interfere with the bite of the user. Even if filed down, the ends of these fins have been

subjected to pressure during mastication whereby the casting post has eventually been worked loose from its position in the casting, necessitating a complete reconstruction of the dental structure. Figure 9 shows how this invention completely eliminates this difficulty and makes it impossible for the plate units to become dislodged. This figure illustrates how the casting post unit does not interfere with the bite, even in cases of "close bite" as indicated in dotted outline at *a a'*. A rigid metal biting or chewing surface is thus provided, together with a removable facing which can be easily replaced by substituting another and cementing it in place. Cast construction is stronger than the usual vulcanite plate, and the interlocked casting post unit is superior to present soldered fastenings or extended fin attachments.

Figure 10 illustrates how a pair of cast teeth, 11 and 12, made in accordance with this invention, can be attached to gold inlays 13 and 14 provided in complementary cavities in adjacent teeth. The construction shown is illustrative merely of a fixed construction but the invention may also be built on a cast metal base or removable bridgework. It should be understood that these cast backings may be secured in place by other means such as crowns fitted on abutment teeth or on plates or other means of attachment known to the art.

The post is preferably made of a high fusing alloy, rich in platinum, with a melting point of 250 degrees Fahrenheit over pure gold, so that it can be invested with the wax model and cast against without danger of partial fusion or distortion.

Obviously this invention is not limited to the precise casting of metal teeth herein illustrated, but may as well be utilized in attaching facing securing means to plates or other dental construction. Vulcanite plates can be molded around the interlocking means to secure effective and permanent attachment thereto. Moreover, it is not indispensable that the various features of this invention be used conjointly, as they may be used to advantage in various combinations and subcombinations.

I claim:

1. An artificial tooth construction comprising a cast backing, a substantially flat plate anchored in and having a flat surface flush with a surface of said backing, said plate being anchored by projecting portions interlocking with said backing, a web extending from said plate, a post formed on said web and being substantially narrower than said plate, and a slotted facing longitudinally slideable along said post and against the flush surfaces of said plate and backing.

2. An artificial tooth construction comprising a cast backing, a substantially flat plate anchored in and having a flat surface flush

with a surface of said backing, said plate being anchored by portions projecting from the edges of said plate and below the surface thereof and interlocking with said backing,
5 a web extending from said plate, a post formed on said web and being substantially narrower than said plate, and a slotted facing longitudinally slidable along said post and against the flush surfaces of said plate and backing.

10 Signed at New York in the county of New York and State of New York this 9th day of April, A. D. 1929.

BENJAMIN K. TAKENAKA.
